UNITED STATES PATENT OFFICE.

GEORG SPIESS, OF LEIPZIG-REUDNITZ, GERMANY.

SHEET-FEEDING APPARATUS FOR PAPER-SORTING MACHINES.

1,348,246.

Specification of Letters Patent.

Patented Aug. 3, 1920.

Original application filed December 28, 1915, Serial No. 69,047. Divided and this application filed August 8, 1918. Serial No. 249,039.

To all whom it may concern:

Be it known that I, GEORG SPIESS, a subject of the German Emperor, and residing at Leipzig-Reudnitz, Germany, have invented certain new and useful Improvements in Sheet-Feeding Apparatus for Paper-Sorting Machines, of which the following is a specification.

In the known paper-sorting machines the paper web winding off the roll is conveyed by means of guide rollers to the longitudinal cutter and then to the transverse cutter. The completely cut sheet is delivered to grippers that convey it over the inspection section to the waste heap, or as "passed" to the laying-off table. In order that the several sheets shall not come in contact with each other they have to be moved along with spaces between them. These spaces allow the support on which or over which the sheet is sliding, to become visible. This circumstance has a disturbing effect upon the eye of the inspector, which is thereby prematurely tired.

Further, in the known machines, the sheet after having been severed by the transverse cutter, falls on to a conveyer. This conveyer, which is ordinarily a web conveyer, acts as a connection between the transverse cutter and the grippers in order that all the sizes of sheet may be handled, and also that the cut sheets may be securely inserted into the grippers. Various circumstances have however an unfavorable effect upon the conveyer that is composed of numerous separate parts, so that it is a great advantage if this conveyer can be dispensed with.

The conveyer must also run at a higher speed than the gripper mechanism in order to allow time for straightening the sheet while the conveyer is continuing its movement. The sudden stoppage in straightening the sheets, has the result more particularly in the case of light kinds of paper, of causing the front edges to become deeply creased or torn. This result is more particularly due to the high speed of the sheets. Moreover, a good deal of waste is caused by the blast, whereby the sheet is lifted off at 50 times from the conveyer and has not time to attach itself properly to the stops. For

the purposes of inspection the speed of the conveyer is further limited by the keenness of the eyesight of the inspector.

These drawbacks are obviated by the improved apparatus wherein the known lateral grippers are employed which grip the sheet by both of its side edges. This gripping device allows of positioning the transverse cutter very close up to the gripping device, so that the sheet when gripped by the grippers can be held mechanically by them until the sheet is separated from the web. Consequently it is possible to dispense with the conveyer which as already above stated, causes a good deal of waste.

Further, the provision of these grippers in combination with the hereinafter described devices, allows of maintaining a constant or approximately constant speed of the paper web and of the grippers for the different sizes of sheet.

Whereas in the known apparatus the several sheets after having been cut, have been left to themselves, in the new apparatus each severed sheet is not released from the grippers because the action of the cutters and the closing of the grippers can take place at the same or approximately the same times.

The improved apparatus also allows in the case of faults occurring in the web, of throwing out short portions of the said web and conveying them on to the laying-off table. The inspector is able to cause the transverse cutter to come earlier into operation than only after the passage of a complete size of sheet. If faults should show themselves at the beginning or at the end of a size of sheet, the improved apparatus allows of cutting off and throwing out the faulty portion of the sheet, whereas hitherto in the case of any fault, the whole sheet in which the said fault occurred had to be thrown out.

A constructional example of the improved apparatus is illustrated in the accompanying drawings in which:

Figure 1 is a longitudinal section,

Fig. 2 a plan, and

Fig. 3 a cross section of the improved apparatus.

Fig. 4 is a section, and

 Fig. 15 is a partial elevation of a diagrammatic arrangement of an apparatus for allowing of inspecting the sheet on both sides.
 Fig. 16 is a side elevation of an operating mechanism therefor, and
 Fig. 17 illustrates a particular construction of this apparatus for varying speeds.
 The paper web winding off the roll *a* is led over the transverse straightening rollers *b* to the drawing rollers *c* which convey the web to the longitudinal cutter *d*, *d'*. After the web has been cut longitudinally, its several constituent webs are conveyed by guide rollers *e*, *e'* to the right and left over an inspection section to the transverse cutters. Each inspection section consists of an endless traveling felt web *F* passing around the rollers *f* and *f'*. Each sheet to be severed is gripped on both sides by grippers *2^a*, *2^b* at the instant of severing, and is conveyed either to the waste heap or to the place where the good sheets are laid off. The grippers *2^a*, *2^b* are carried by closed chains *1^a*, *1^b* which pass over the chain wheels *3* and *4*. The grippers are supported by guides *k* and *k'* on which the grippers roll (Fig. 3).
 When the inspector discovers a fault in the paper, he presses a hand lever *l* to the end *l'* of which there is connected a rod *m*. The motion is transmitted to a bell crank lever *n* which is fulcrumed on the pin *o* and in rotating causes through the medium of the rod *p*, a rotation of the bell crank lever *q'* that is fulcrumed on the pin *q*. This movement releases the roller lever *r* which is pivoted on the pin *s*, and which is thereby pressed by the spring *u* with its roller *r'* against the periphery of the cam disk *t*. When the sheet is situated above the place where the waste is to be deposited, the roller *r'* is pulled by the spring *u* into a recess of the cam disk *t*, and the arm *r²* of the roller lever *r* moves down. The rod *v* transmits the motion to the lever *w* which is fulcrumed on the pin *x*. To the lever *w* there is connected the rod *y* which is attached to the pin *z* of the lever *A²*, whereby the opening rod *A³* is depressed which is suspended

from the rocking arms *A¹* and *A²*, mounted on pins *A⁴* and *A⁵*. In the descent of the opening rod *A³* the stop levers *G¹²* of the hereinafter described gripper *2^a* are released, so that all the grippers *2^a* and *2^b* which are situated at the time under the opening rod *A³*, are opened so that they release the respective sheet.

The lever *w* also serves through the medium of a second rod *B* to move the gripper-closing curve *B⁴* which is carried by the rocking arm *B²* fulcrumed on the pin *A⁴*, and by the bell crank lever *B³* fulcrumed on the pin *B¹*. By this means the described rotation of the cam disk *t* at the same time depresses the opening rod *A³* and raises the gripper-closing curve *B⁴* so that the gripper-closing curve is rendered inoperative at the instant of opening the grippers.

The striker *C* is fixed on the shaft *x* so that as the shaft *x* rotates, the said striker makes a downward oscillation and compels the sheet to fall quickly on to the sorting heap.

The laying-off of the sheets that are without fault is controlled by the cam disk *H* which is mounted on the revolving shaft *W²*, and which actuates the roller lever *H¹* that is fulcrumed on the pin *H²*. By means of a bell crank lever *J* mounted on the shaft *J¹*, a rod *J²* and the opening rod *J⁶* suspended from the rocking arms *J³*, *J⁴*, are shifted. On the shaft *J¹* there is also mounted the striker *S* which moves down together with the gripper opener.

The grippers *2^a*, *2^b* consist of two movable gripper plates *G¹* and *G²* (Figs. 6-8). The upper gripper plate *G¹* is pivoted on the pin *G³* and its boss is constructed as a toothed segment; it is actuated by means of a toothed segment arm *G⁴* which is pivoted on the pin *G⁵*. The lower gripper plate *G²* which is likewise pivoted on the pin *G³* is connected by a connecting rod *G⁷* to the segment arm *G⁴* in such a manner that the movement of the latter will cause the two gripper plates to make opposite movements. The moving of the segment arm and the closing of the gripper is produced by the depression of the roller pin *G⁸* when its roller *G⁹* rolls over the closing curve *B⁴*. In the descent of the roller pin *G⁸* the compression spring *G¹⁰* is compressed until the arresting lever *G¹²* is caused by the spring *G¹¹* to arrest the segment lever *G⁴*. The opening of the grippers is effected by the opening rods *A³* and *J⁶* moving down on to the free end of the arresting lever *G¹²* until its nose releases the segment lever *G⁴*. By this means the compression spring *G¹⁰* comes into operation and presses the upper gripper plate *G¹* in the upward direction, and the lower gripper plate *G²* in the downward direction, through the medium of the link *G⁷*. The gripper casing is jointed to the links of

 130

the chain 1^a, 1^b and carries guide rollers G¹⁵ by means of which it bears upon the guides k.

In order to work the machine economically, a revolving transverse cutter is employed, so constructed that when a fault is found in the paper web at the commencement of the sheet to be severed, only the first portion, namely that which contains the said fault, of the sheet is cut off and conveyed to the waste heap. This new transverse cutter which is illustrated on a larger scale in Figs. 4 and 5, is so constructed that faulty sheets as stated can be severed from the paper web after only a half revolution of the transverse cutter, so that only half sheets go to waste.

The transverse cutter which is caused to cut prematurely or in half the usual time, by means of the hand lever l, may work at the same time as the striker C and the opener A³. If for instance a lever D is pivoted on a pin m¹ on the rod m, which lever is fulcrumed on the pin D¹, then the lifting of the rod m will cause the other end of the said lever to move down, whereby the roller lever E is caused by the spring E² to come in contact with the cam disk k which is mounted on the shaft W. The shafts W, W¹ and the aforesaid shaft W² have equal numbers of revolutions. To the other end of the roller lever E there is pivoted a rod E¹ which is guided in the bearing E³ and carries a driving tooth E⁴ which engages with the ratchet teeth of a cam disk E⁵ (Figs. 4 and 5). The cam disk revolves on the shaft E⁶.

The transverse cutter consists of two knives M and M¹ mounted on two arms arranged 180° apart. The arms carrying the knives have an oval bore for the purpose of enabling the arms to be shifted transversely across the cutter shaft M³. Feather keys M⁴ serve to guide and actuate these arms. On the bearing M² there is arranged a forked lever M⁵ fulcrumed on the pin M⁶. This lever engages by means of its fork the revolving transverse cutter knife-holder, and it carries at its other end a roller M⁷ that engages in the curve of the cam disk E⁶. At each upward movement of the rod E¹ the curve is rotated on the shaft E⁶ through a certain distance, the curve by altering the direction serving to reverse the forked lever M⁵ and to move the knife-holder laterally on the shaft M³, so that the second knife M¹ will come into operation after only a half revolution of the shaft M³. By this means only a half sheet is severed as waste from the paper web, and conveyed to the waste heap.

After the initial cut the knife M¹ will now continue to cut only at each complete revolution of the cutter shaft until, on the occurrence of a faulty space in the sheet, the apparatus is employed in the above de-

scribed manner to sever by means of the knife M a half sheet as waste and to throw it out, whereupon the knife M will continue to cut. The apparatus has therefore the great advantage of giving a better yield of 70 good sheets.

In order that the instant of closing the grippers may be varied in view of the changing of the size of sheet that is to be cut, and yet the cutting of the sheet and the closing 75 of the grippers shall take place at the same or approximately the same times, the gripper-closing curve B⁴ is made adjustable. In the constructional example illustrated in Fig. 5^a, the horizontally adjustable gripper-closing curve B⁴ is for this purpose suspended only indirectly from the actuating arms B² and B³. To these arms there is directly pivoted a rail B^a carrying a bar B^b. The gripper-closing curve B⁴ is mounted movably on this bar and can be fixed in any position of adjustment on said bar by means of a screw or other clamping device. According as the gripper-closing curve B⁴ is moved to the right or to the left on the bar 80 B^b, the grippers 2^a, 2^b are closed at an earlier or later moment.

A further mechanism for varying the time of opening and closing the grippers within wide limits is illustrated in Figs. 9-11, in 95 its application to another system of grippers. The gripper-closing mechanism consists of a length of jointed chain 23 passing over the chain wheels 25 and 27. To the ends of the chain there is attached a steel 100 ribbon 24 which passes over a pulley 26 so that the chain and the steel ribbon constitute a self-contained body. The chain links are of U-shape and of such nature that the outer connecting members of each link of 105 the chain, are arranged in a plane surface. The gripper chains 1^a and 1^b which travel horizontally in this arrangement, pass around the pulleys 3, and the hereinbefore described mechanism is located within this 110 closed gripper chain. In addition to the pulleys 3 there is also provided an arc-shaped gripper opening section 15 in such a manner that the adjusting levers 21 for each gripper in traveling over the gripper opening sec- 115 tion 15, will bear against the latter and keep the grippers open. The adjusting levers 21 pass from the extended limb 15^a of the gripper-opening section to the chain 23, and bear then upon the closed portion of the U-shaped 120 links of this chain. Only when the adjusting levers 21 have moved away from the last of the links of the chain 23, are the grippers closed by the action of a compres- 125 sion spring contained in the gripper casing, said spring acting upon the sliding mem- ber 19 which presses the gripper plates 16 and 17 against each other. A rail 28 behind the limbs of the chain 23 serves to support the same. Now if the closing of the grip- 130

pers is to take place sooner or later, then by merely rotating the axle 29 around which the ribbon 24 travels, it is possible to vary the position of the last link of the chain 5 23 relatively to the gripper-opening section 15. The axle 29 is for this purpose formed with a square portion upon which a crank handle is placed for effecting the adjustment.

The provision of a running-up chain of 10 this kind allows of shifting the closing of the grippers within very wide limits and with a compact construction. If compactness is not necessary, then such a shifting of the time of the closing of the grippers may be effected 15 by adding straight extension pieces of various lengths to the free limb 15^a of the gripper opening section 15.

An adjustable gripper-closing curve of 20 the kind hereinbefore described assumes its full constructional importance when the speed of the grippers is made variable. Namely, if it is required to increase or diminish the space between the successive sheets, then the gripper speed will have to 25 undergo a corresponding variation in order that each time a sheet has been severed, the conveying away of the same shall take place with sufficient rapidity to allow of the desired intermediate space being left. A 30 change in the gripper speed renders it also necessary to correspondingly alter the closure of the first grippers and this purpose is served more particularly by the adjustability of the gripper-closing curve. For the 35 purpose of varying the gripper speed the most various devices may be employed. A constructional example is illustrated in Figs. 12-14.

In this arrangement the chain wheels 3 40 around which pass the gripper chains 1^a and 1^b, are driven by a change wheel gear contained in the casing 30. The change wheels 31 are constructed in the known manner as stepped toothed wheels, and the 45 chain wheels 32 are correspondingly constructed. By means of a hand lever 33 one or the other gear can be thrown into operation. In the example shown the coupling sleeve 47 which is shifted by the lever 33, 50 is provided with a feather 48 on the free end of which there is a driving nose 49. The feather engages in a corresponding recess in the axle on which the change wheels 32 are freely rotatable.

55 By means of the driving nose 49 one or the other of the change wheels are carried around by the revolving shaft according to the position of the lever 33.

For the present invention it is immaterial 60 what particular construction is chosen for these change wheel gears and their operation. The same purpose might be served by employing a friction wheel gear of known type for varying the speed.

65 If with the employment of the hereinbe-

fore described construction of the adjustable gripper-closing curve, the latter be so adjusted that the closing of the grippers in the case of the first grippers takes place at the same time as the cutting of the transverse cutter, the sheets will be conveyed away without spaces between them, if at the same time the speed of the grippers is so adjusted that it corresponds to the speed of the unwinding paper web. But if on the contrary the closing of the grippers takes place only at approximately the same time as the cutting of the cutters, and the grippers have a somewhat greater speed than the unwinding paper web, then the desired 70 spaces will be left between the successive 75 sheets.

Apart from the normal speed of inspection, the output of an apparatus for sorting out faulty sheets of the kind described, 80 depends only on the speed of unwinding of the paper web.

The greatest output will be obtained by placing the point of inspection in front of the transverse cutter, as set forth in the described constructional example, because at this point the speed of unwinding of the paper web may be increased up to the highest permissible speed of inspection by the 90 inspector.

If for the purpose of saving space or for other reasons, it is desired to place the point of inspection behind the transverse cutter, that is to say, if it is desired to place it above the gripper path, then the arrangement as shown may be employed in the case of papers which allow of the sheets succeeding one another without intermediate spaces between. On the contrary, in the case of light sorts of paper or sheets of large size 105 that require a certain time for settling down upon the pile, it is necessary to have intermediate spaces between the successive sheets, which spaces may be of various amounts.

This would have the result that the placing of the point of inspection over the gripper path, will reduce the output in proportion to the size of the intermediate spaces if the speed of inspection is to be normal.

This drawback may be removed by the 110 following arrangement illustrated in Figs. 15 and 16, for inspecting the paper sheets. In this arrangement it is assumed that there is an inspection point in front of the transverse cutter and also behind the same above 115 the gripper mechanism, this arrangement having the further advantage of enabling the paper web to be inspected from both sides. The paper web winds off the roll *a* and is led over a reversing roller *a*¹. The first inspection point is placed between *a* and *a*¹. The further travel of the paper web is the same as in the usual apparatus. If, in view of the fact that an inspection point is placed above the gripper mecha- 120 125 130

nism, it is desired also to give to the latter the same speed as that of the winding-off paper web, that is to say, to attain the highest permissible speed of inspection, and if 5 it is desired to leave at the same time intermediate spaces between the successive sheets so as to obtain sufficient time for laying-off, then the speed of the gripper mechanism must be accelerated during the period when 10 the sheet is being severed from the web by the transverse cutter.

For this purpose there may be employed for instance the following mechanism for driving the chain wheels 3.

15 For driving the gripper chain wheels 3 there are arranged on the driving shaft W a pair of bevel wheels 36 and 37, of which 36 is fast and 37 is loose. On the same boss as the last mentioned wheel there is arranged 20 the driving wheel 3³ by which the gripper chains are actuated. A connecting bevel wheel 39 is arranged between the two bevel wheels 36 and 37 in such a manner as to engage simultaneously with both those 25 bevel wheels. Its bearing sleeve 38 is likewise freely rotatable on the shaft W. A roller arm 40 on the upper end of the axle of the bevel wheel 39 engages in the curve of a cam disk 41 mounted on a shaft 50 30 which is driven by means of toothed wheels 34, 35 from the main shaft W. By rotating the cam disk the bevel wheel 39 can be maintained in its position of rest, namely so long as the roller 40 is running in the circular 35 arc of the curve. On entering the curved portion however the carrier of the bevel wheel 39 will be caused to rotate on the shaft W. If this rotation has the same direction as the rotation of the bevel wheel 40 37, this will accelerate the rotation of this wheel and consequently also the rotation of the gripper mechanism. On the return of the bevel wheel 39 into its initial position, the gripper mechanism will however assume 45 the same speed as it had before, which may be equal to that of the paper web. By this means as each new sheet is fed, its speed of conveyance is temporarily altered at the desired moment, but this alteration is immediately 50 canceled as soon as the sheet to be inspected has passed through the second place of inspection above the gripper path.

55 For the purpose of varying the intermediate spaces the hereinbefore described driving mechanism may also be constructed as shown in Fig. 17. In this arrangement the cam disk 41 does not act upon the bevel wheel 39 directly, but indirectly through the medium of an intermediately fulcrumed 60 lever 42 carrying in an adjustable manner upon its free end a pivoted arm 43. This pivoted arm is pivoted at one end to the carrier of the bevel wheel 39 and at its other

end to a sleeve 45 which is slidable along the free end of the lever 42, and can be fixed 65 to it in any position by means of a clamping screw 46. When the motion of the cam disk is transmitted through these intermediate members 42 and 43 to the bevel wheel 39, the travel of the bevel wheel 39 along the 70 axle W is thereby varied according as the pivoted arm 43 is connected nearer to or farther from the center of oscillation 44 of the lever 42. The variation of the travel of the wheel 39 entails also a variation in 75 the speed of the conveyance of the sheets and consequently a variation of the intermediate spaces between the successive sheets.

Such a construction of the improved sheet-sorting apparatus will give the greatest possible output irrespectively of the sizes of the sheets, not only as regards the number of the sheets, but also more particularly the weight of the sheets.

This improved arrangement may also be 85 adopted for sheets that follow immediately upon one another, that is to say, where no intermediate spaces are left between the successive sheets. Nevertheless, the intermediate spaces necessary for laying-off may 90 be retained. In any case it is possible to increase the output to a maximum in view of the sorts of paper to be treated and the sizes of sheets to be dealt with which are to be laid-off with or without intermediate 95 spaces between the successive sheets, while retaining in both cases an unchanged speed of inspection.

The subject matter of this application was the subject of application No. 69,047, filed 100 December 28, 1915, of which this application is a division.

What I claim is:—

In a paper sorting machine, a sheet feeding apparatus for sheets cut from a moving 105 web, grippers, flexible members for carrying the grippers, guiding means for the gripper carriers, means for varying the speed of the flexible members whereby spaces can be produced between successive 110 sheets with the speed of the sheet at the place of inspection equal to the unwinding speed of the paper web, said speed varying means comprising a beveled gear on the gripper driving shaft, a driven bevel wheel 115 of said gear being mounted to rotate with the driving wheel of the drive for the flexible member on the shaft, and a transmitting bevel wheel likewise rotatable with respect to said shaft and a roller arm on a 120 support of said wheel engaging a cam driven from said shaft.

In witness whereof I have hereunto set my hand.

GEORG SPIESS.
